UNITED STATES PATENT OFFICE.

ROBERT S. MOSS, OF CHICAGO, ILLINOIS, ASSIGNOR TO L. Z. LEITER, OF SAME PLACE.

PROCESS OF MAKING COAL-GAS.

SPECIFICATION forming part of Letters Patent No. 679,059, dated July 23, 1901.

Application filed December 17, 1900. Serial No. 40,149. (No specimens.)

To all whom it may concern:

Be it known that I, ROBERT S. MOSS, a citizen of the United States, residing at Chicago, in the county of Cook and State of Illinois, 5 have invented a certain new and useful Improvement in Processes of Making Coal-Gas, of which the following is a specification.

The usual practice in the manufacture of coal-gas requires in the process the employment of a furnace external to the apparatus 10 where the gas is generated.

The process of the present invention has for its object the manufacture of coal-gas, either illuminating or heating, by the employment 15 of what is known or termed a "coking-oven" of the beehive type without the assistance of any furnace or other heating appliance additional to the oven itself, and the process is of such a nature that by the means 20 employed coal-gas, either illuminating or heating, as may be desired, is obtained in addition to the production of tar and ammoniacal liquor from the coal, as is usual in the manufacture of coal-gas, and these results are accomplished 25 during the operation of coking the coal and without impairing the quality of the coke produced and without the assistance of a furnace or other heating appliance external to the oven.

30 The invention consists in the several proceedings and steps hereinafter described, and pointed out in the claims.

The carrying out of the process requires the employment of a beehive coking-oven having 35 certain peculiarities of construction, and an oven of this description is illustrated in the drawings, in which—

Figure 1 is a horizontal sectional elevation of an oven adapted to attain the object and 40 purpose of the invention. Fig. 2 is a front elevation showing the body of the oven in dotted lines back of the front protecting-wall of a battery of ovens; Fig. 3, a vertical sectional elevation showing an oven adapted for 45 use in carrying out the process and provided with a flue for heating the bottom of the oven with the waste consumed gases; Fig. 4, a horizontal sectional elevation on line 4 of Fig. 3, showing the heat passage or channel in the 50 bottom of the oven; Fig. 5, a detail in section showing the construction of the bottom of the

oven of Figs. 3 and 4, and Fig. 6 a detail in cross-section of the bottom of the oven of Figs. 3 and 4.

The drawings, with the exception of Fig. 2, 55 show only a single oven; but it is to be understood that either a single oven or a battery of ovens can be used in connection with the process, and with a battery of ovens the ovens which constitute the battery are to be 60 suitably connected together, as is the custom with the construction of coke-ovens arranged in series of battery form.

The oven is of the general type of what are known or termed "beehive coking-ovens," 65 and, as shown in the drawings, this oven is formed with a wall A and a bottom B, inclosing a coking-chamber C. The coking-chamber has external air supplied thereto to support combustion and to produce an intense 70 heat by means of apertures or openings D, arranged in the wall A at different points, each with an inclination in different directions, so as to produce a circulating blast through each aperture or opening, and, as 75 shown, the apertures or openings have an upward inclination, so as to insure the carrying of the blast over the mass or charge of coal in the coking-chamber. The external air is projected through each aperture or opening 80 from a nozzle or discharge-pipe D'; entered into the aperture, and each nozzle or discharge-pipe is connected with a common supply-pipe D², receiving a supply of air through a pipe D³ from any suitable source of supply 85 that will cause the air to be supplied to the pipe D² under pressure. The top of the oven has therein the usual trunnel-head E, with its charging-opening, and at one side the wall is provided with the usual opening F for withdrawing the coke.

The bottom of the oven has therein on each side of the center a channel or passage G, each extending, in the arrangement shown, diagonally from the front toward the rear of 95 the oven and each having its top provided with perforations or slots which open into the coking-chamber beneath the mass or charge of coal when in the chamber. Each passage or channel extends through the front wall of 100 the oven and has connected therewith a pipe H, which leads to and is sealed in a hydraulic

main (not shown) in the usual manner of entering and sealing pipes in the hydraulic main for gas apparatus, and each pipe H has a controlling-valve for opening or closing the 5 pipe, as may be required. The coking-chamber has in the wall thereof an opening into which the end of a pipe I leads, which pipe is extended to the same hydraulic main as the pipes H and is sealed therein in the usual 10 manner. The channels or passages G, with their conducting-pipes H, furnish the means for withdrawing the gas and products of coking, such as tar and ammoniacal liquid, from the bottom or lower portion of the coking-chamber, and the pipe I furnishes the 15 means for withdrawing the gas and products of coking from the top or upper portion of the coal, so that in operation the gas and other distilled products will be drawn by one eduction or the other from the entire mass or 20 charge of coal.

It is desirable in employing the process to furnish a uniform heat throughout the mass or charge from the top to the bottom thereof, 25 and an arrangement for this purpose is shown in Figs. 3 and 4, in which a flue J is formed with or attached to the wall of the oven, with its mouth opening into the coking-chamber, at the top thereof, and its lower end communicating with a passage K, formed in the bottom of the oven, by means of vertical partitions, each alternate partition terminating short of the wall of the oven, so as to leave an opening at its end, forming a sinuous 30 or zigzag passage or channel for the heat to travel beneath the coking-chamber and finally discharge at a flue L, the lower end of which communicates with the bottom passage or channel for discharging the gases carried through the bottom into the atmosphere, 35 and this discharge-flue can be formed with or attached to the wall of the oven. The flue J is controlled by a damper M, the stem or handle of which extends through the wall of the oven, so that the damper can be moved or turned to have the flue opened or closed, 40 as required. The consumed gases at the upper portion of the coking-chamber are of a high degree of heat, and these gases are drawn into the mouth of the flue J when the damper M is open and carried down therein to enter the sinuous or zigzag passage or channel K and travel in such passage beneath the bottom of the coking-chamber, and by reason 45 of the high heat of these gases the bottom of the coking-chamber becomes highly heated from the passage of the gases therethrough, and this highly-heated bottom acts upon the bottom or lower portion of the mass or charge 50 of coal, imparting heat thereto, which heat acts to evolve and expels the gas and volatile matter from the bottom of the mass or charge for such evolved and expelled gases and volatile matter to pass upward through the mass or charge and mingle with the air-blast projected into the coking-chamber, increasing combustion and as a necessary result increas-

ing the temperature, and at the same time the operation of evolving and expelling the gases and volatile matter is conducted throughout 70 the entire charge or mass of coal instead of at the upper portion thereof, as would be the case with a cool bottom instead of a hot bottom for the coking-chamber.

The coking-chamber is supplied with the 75 charge or mass of coal to be coked through the trunnel-head E, and when the charge is entered into the coking-chamber the front of the oven is sealed and the trunnel-head left open, as usual in the operation of coking coal. 80 After the coal ignites a blast of air sufficient to create complete combustion and produce a distillation of the coal is entered into the coking-chamber, and when a sufficiently-high 85 temperature has been obtained the supply of air is shut off, the oven is made gas-tight, damper M is closed, the proper gas-valve is opened, and the products of distillation collected in the manner hereinafter set forth. The blast of air can be entered through the 90 openings D in the coking-chamber above the mass or charge of coal or be entered into such chamber through suitable supply pipes and openings or perforated oven-bottom at the bottom of the mass or charge; but in 95 either case after an air-supply of the requisite amount to raise the temperature sufficiently high to produce distillation has been entered the supply is to be shut off.

The process of withdrawing the gas and distilled products is carried out through the 100 eduction channels or passages in the bottom of the oven or through the eduction-pipe I, which is situated just above the mass of coal in the oven. The lower eduction passages or 105 channels and their connecting-pipes on the bottom are employed when the ignition and combustion is from above, which will be the case when the air-supply is admitted into the upper portion of the coking-chamber, in which 110 case the gas and the distilled products are drawn down through the mass or charge of coal into the eduction passages or channels to enter the pipes and be discharged into the hydraulic main for further treatment, as is 115 usual in the production of coal-gas. The upper eduction-pipe I is employed when the air-supply for combustion is entered at the bottom of the coking-chamber, in which case the 120 ignition and combustion will be from the bottom, and the coal-gas and distilled products will be drawn upward to pass out through the upper pipe and enter the hydraulic main for the usual treatment of coal-gas.

The process can be practiced to the best 125 advantage with an oven having the capability of receiving air for supplying and maintaining combustion both at the top and bottom of the mass or charge of coal; but it is to be understood that for some purposes and 130 with some kinds of coal either one or the other of the air-supplies alone can be employed, as best adapted for the treatment of the coal, and this can be determined upon

from the nature of the coal by an analysis and from its physical properties. The process embodies the principle of heating either the top or bottom layer of the mass or charge 5 of coal to a fairly-high temperature, then shutting off the air-blast, closing up the oven, making it gas and air tight, and then by opening the valve of either the eduction-pipes H or the eduction-pipe I connecting the oven 10 with the hydraulic main to withdraw the products of distillation from either the top or bottom, according as to whether the distillation of the coal is at the top or bottom layer thereof. If the combustion, before making 15 the oven gas or air tight, takes place at the upper portion of the mass or charge, the eduction of the gas and distilled products will be from the bottom of the mass or charge through the passages or channels and their 20 pipes; but if the combustion, before making the oven gas or air tight, takes place at the bottom of the mass or charge the withdrawal of the gas and distilled products will be from the top through the eduction-pipe I, 25 and such distillation will continue in either case so long as the walls of the oven retain a sufficient amount of heat to produce the required distillation. It will be understood 30 that the distillation will continue for a longer or shorter period of time, depending upon the heat retained by the walls of the oven, by the heat of the layers of coal, by the readiness with which the volatile matter is evolved and 35 expelled, and also by the amount of volatile matter contained in the coal under treatment, and upon these conditions also will depend the period of drawing off the gas and distilled products before renewing the charge of air for further treatment of the coal.

40 The combustion of the coke on the bottom of the oven should be prevented after the whole of its volatile matter has been expelled and it is found necessary to admit air through the bottom, so as to increase the temperature 45 in the interior of the mass of coal, and for this purpose the products of combustion from the top of the oven can be returned to the bottom and there mixed with the air, thus diluting the oxygen of the air to such an extent 50 as to prevent combustion of the fixed carbon, while it will readily consume a portion of the volatile matter in the interior of the mass or charge. By this means the temperature of the interior of the mass or charge 55 is raised sufficiently high for the continued distillation of the layer of coal above it. The air-supply is then shut off, the oven made gas or air tight, the upper eduction-valve opened, and the products of distillation are 60 drawn off.

When the temperature has fallen below the point of distillation, the proper eduction valve or valves is or are closed and the oven is again opened up and recharged with a 65 blast of air to produce rapid combustion, thus again raising the temperature of the coal. In so doing it may be well to reverse

the blast—that is to say, if in the first operation the air was blown in at the top of the coking-chamber the next operation should 70 have the air blown in at the bottom of the chamber, and, if necessary, the bottom of the chamber can be heated by opening the flue J, so as to supply the bottom of the oven with heat from the highly-heated consumed gases. 75 It will be understood that when the necessary supply of air is projected into the chamber either at the top or bottom, the supply is to be regulated in proportion to the evolved volatile matter expelled from the coal, thus 80 again bringing it into a condition for rapid distillation, and the evolving of gases and volatile matter to be again drawn off until the temperature falls below the point of distillation. The gas, tar, and distilled liquors 85 should preferably be made to pass off through the eduction-passages or channels in the bottom of the oven when the air-supply is entered at the top, and when the air-supply is entered from the bottom the gas, tar, and 90 ammoniacal liquor should preferably be made to pass off from the top, as by this arrangement the heavy gases do not pass through a hot layer of coke or coal, which would crack them up into lighter gases, thus reducing the 95 illuminating power by deposition of carbon. The process of alternately drawing the gas and distilled products from the top and bottom of the mass or charge is continued until the entire mass or charge has been operated 100 upon, when the resultant product will be a coke of a high degree of efficiency, it being understood that after the entire amount of gas and distilled liquid which can preferably be expelled is drawn off, leaving only sufficient 105 for coking the coal, the remaining portion of the charge or mass is to be treated by leaving the oven open for the admission of the air-blast, if necessary, and so proceed with the coking until completed. If care is 110 taken not to withdraw too much of the volatile matter from the coal before proceeding with the final coking process, the resultant coke will be equal to and in some cases superior to that obtained in the ordinary process 115 of coking, and this coke will be in addition to the gas, tar, and ammoniacal liquor obtained by the operation of the process in the production of gas.

My process operates to withdraw in an un- 120 consumed condition all volatile matter which is not necessary to the production of heat for the operation of coking the coal, and in use the heat of combustion and of the oven is utilized to throw off the volatile matter to an 125 extent only that will leave a remainder sufficient to continue the production of coke from the coal, and the volatile matter thus thrown off is collected in the form of gas, tar, and liquor and withdrawn through the eduction- 130 pipes and delivered to the hydraulic main for such further treatment common to the production of coal-gas as may be necessary. The result of the process is the obtaining of a

good quality of coke and in addition thereto the saving of the volatile matter which heretofore has been wasted in the production of coke. It is well known that in the treatment 5 of coal for the production of coke there is always a considerable margin between the total heat represented by the combustion of the volatile matter and the heat necessary to coke, and it is this difference which is saved by the 10 use of my process. It is also well known that only a very small quantity of the heat generated in coking coal and obtained from its volatile matter is made effective. It is this 15 waste volatile matter which is utilized and rendered effective in my process, thus saving a large portion of the total volatile matter in the form of gas and tar, with the nitrogen in the coal saved in the form of ammoniacal liquor. The amount of gas, tar, and liquor obtained 20 per ton of coal coked will depend upon the amount of volatile matter in the coal, its facility for coking, and the temperature at which the volatile matter is evolved and expelled; but in any case a greater or less 25 amount of gas, tar, and liquor will be produced and saved by the employment of my process.

When it is desired to obtain producer-gas, my method or process is used by blowing air 30 into either the top or bottom of the mass or charge of coal; such air being regulated so as to insure a partial combustion of the volatile matter in the coal, at the same time drawing off through the eduction pipe or 35 pipes the consumed gases, together with the unconsumed volatile matter. This drawing off is reversed from time to time, the air being blown in at the bottom and the gases taken off through the upper eduction-pipe, 40 afterward blowing air in the top and drawing the gases off through the lower eduction-pipes, and this plan of an upper and lower blast and reverse drawing off is continued for such length of time as is necessary without 45 injury to the fixed carbon. The length of time necessary can only be determined from the nature and properties of the coal, its amount of volatile matter, and the rapidity of its expulsion under varying degrees of 50 heat. The volume of gas obtained and its heat units per cubic foot can by this process be varied at will. For instance, if the oper-

ation is conducted at a low temperature, less gas will be obtained, the heat units of which per cubic foot will be very high, and more tar 55 than when operated at a higher temperature. At a very high temperature a large volume of gas will be obtained, the heat units of which per cubic foot will be very small, and no tar. Between these extremes by my process 60 gases of almost any degree of heat per cubic foot can be obtained. The maximum amount of heat which it is possible to obtain per cubic foot of gas will depend upon the amount of volatile matter in the coal and the 65 manner of operating.

By the use of my process there can be obtained at will a gas very high or very low in heat units, thus giving a greater range and that, too, in a much more simple manner than 70 has heretofore been possible with any other process.

What I claim as new, and desire to secure by Letters Patent, is—

1. The process of producing coal-gas, which 75 consists in charging a beehive coking-oven with coal, admitting air to the coking-chamber of the oven to produce combustion and heat the walls of the oven and the charge or mass of coal, making the oven gas-tight, after 80 closing the air-supply, for the heat to distil the gases and volatile matter, and alternately educting the distilled gases and products from the top to the bottom layers of the charge or mass of coal, substantially as described. 85

2. The process of producing coal-gas, which consists in charging a beehive coking-oven with coal, admitting air to the coking-chamber of the oven to produce combustion alternately at the top and bottom of the mass or 90 charge of coal, and heat the walls of the oven and the charge or mass of coal, making the oven gas-tight, after closing the air-supply, for the heat to distil the gas and volatile matter and educting the distilled gas from the 95 bottom when the combustion is at the top of the mass or charge of coal and from the top when the combustion is at the bottom of the mass or charge of coal, substantially as described.
